Attorney.

UNITED STATES PATENT OFFICE.

POWEL CROSLEY, JR., OF CINCINNATI, OHIO, ASSIGNOR TO THE FRANK F. TAYLOR CO.,
OF NORWOOD, OHIO, A CORPORATION OF OHIO.

BABY WALKER.

Application filed November 20, 1922. Serial No. 602,241.

My invention relates to improvements in devices for the care of very young children; and more especially to such devices as that disclosed and claimed in the patent to James I. Carroll, 1,492,202, Apr. 29, 1924, on which my invention is an improvement.

Its object, in common with that of the just mentioned prior invention, is to amuse the infant while assisting it to learn to walk, 10 enabling the infant to use its arms and legs freely and to be unhindered in near approach to objects, at the same time supporting the infant, preventing it from getting off the device or overturning; and to accomplish this by a very inexpensive device. The especial object of my improvement, over the prior invention, is to provide for travel of the infant freely in any direction, by a forward rolling support which will at the same 20 time insure stability of the device at the front, necessary for small infants as distinguished from vehicles for larger children. Other objects will appear in the course of the ensuing description.

25 I attain these objects by the device illustrated, for example, in the accompanying drawing, in which—

Figure 1 is a perspective view of the device in use, an infant seated thereon and 30 supported thereby being indicated by dotted lines;

Fig. 2 is a longitudinal vertical section of the device, the body support being in elevation; and

35 Fig. 3 is a perspective view of the front part of the device with a substituted front rolling support.

As I prefer to construct my invention, it 40 comprises a bed 1 of flat elongated shape with a rear wide seat part 2 and a narrow front part 3, joined by smooth curves 4. The rear bolster 5 has its narrow top fixed to the bottom of the rear part of the bed 1 by suitable fastening means 6, and curves 45 down to thinner end parts 7; the bottom being straight, and an axle 8 being secured therealong with end parts 9 projected past the respective ends of the bolster 5, on which rear wheels 10 turn loosely. A brace 11 extends up to the bed 1 at the middle.

The foregoing details are similar to those 50 of the prior application mentioned; as also is the body support, comprising the rear post 12 and front post 13, having shanks 14 fitting in holes in the bed 1, and carrying, near

their tops, a ring 15 passing through holes transversely through the posts. I make the rear post wide, forming a better support for the infant's back. These posts are detachable from the bed, and fold together on the 60 ring 15, for packing, as in the prior application.

In my invention, the front bolster 16 resembles the rear bolster 5 in having a narrow top, fixed to the bottom of the bed near the 65 front end thereof, with a brace block 17 at its rear, up against the bed. This front bolster 16 is of about the same lateral extent at both sides as is the rear bolster 5, and is curved similarly; but instead of an axle and 70 wheels, it carries casters 18 on its bottom near its respective ends. Preferably, it is cut away at its bottom throughout its middle part, leaving downwardly extending legs at the ends, on which the casters are mounted, 75 with their stems up in holes bored in the bottoms of the legs. As these casters 18 can turn freely in any direction on the vertical axes of their stems, as well as roll freely on the floor or ground, they permit the infant 80 to guide itself in any direction by engagement of its feet with the floor or ground, as indicated in Fig. 1. At the same time, being located far out laterally, the casters 18 act to prevent overturning of the device in a 85 diagonally forward direction at either side.

Such a precaution is necessary for the use of a small infant, at the age before it can walk, as it cannot be relied upon to keep itself and the device upright, in its travels, as 90 can an older child with any ordinary velocipede device. As illustrated in Figs. 1 and 2, the support made up of the posts and ring, or otherwise constructed to encircle the child's body at or above its waist line while 95 the child is seated astraddle of the narrower bed part 3, upon the wider bed part 2, confines the child to the device; yet as this is the only encircling means, there is no hampering of the legs and arms, and no hindrance to close approach of the infant, with the device, to objects that may attract its attention. This contributes better to the child's amusement than a device having much laterally extended structure lower down, as in 100 105 various baby-walkers heretofore disclosed. In these respects, my device is similar to that of the mentioned prior application. My improved front support provides against any tipping, as just mentioned, and avoids con-

tact of any non-rotary part with the floor or ground; in this respect being different from any device with outriggers auxiliary to a single front rolling support.

- 5 For use of the child after it is older, the front bolster 16 is detachable, as seen in Fig. 2, where the front part of the bed 1 has an opening 19 up through it, fitted by a plug 19' which opening, upon removal of the 10 bolster 16 and plug 19', may receive the stem 20 of a single large roller or wheel 21 up through it, with the bed 1 resting on a shoulder of the wheel mounting 22. A washer 23, held by a pin 24 through the stem 20, holds 15 the mounting up in the bed 1; and at its top the stem 20 has transverse handles 25 to be grasped by the child for guiding the device. When so used, by the older child, the body support is not needed for such child, and 20 may be removed. The device thus is of especial utility for the very young infant; and its period of usefulness may be prolonged through a later period of the child's life, by the substitution of the hand-guided means 25 as just described.

Modifications may be made, either of the device as used for very young children, as shown in Figs. 1 and 2, or of the substituted means for older children, as in Fig. 3. I 30 have illustrated a design for the front bolster, with its widely laterally spaced legs, which is very simple and economical; but this, as well as the other details, is subject to variation within the scope of my invention. Therefore I do not wish to be understood as being limited to the precise showing and description herein, but having thus fully 35 described my invention,

What I claim as new and desire to secure 40 by Letters Patent is:

1. In a baby-walker, a seat structure, wheels on the rear of said structure, lateral casters on the front part of said structure, said casters being removable from said 45 structure, and said structure having means

to receive a substitute front rolling support, and means detachably connected with said structure to confine and support the body of a child upright thereon when astraddle of said structure, said lateral casters serving 50 to prevent lateral or forward diagonal tipping of said structure with the child supported as aforesaid, while permitting variable curvilinear travel of the structure.

2. In a baby-walker, a seat structure, rear 55 wheels on said structure, front rolling supporting means for said structure permitting variable curvilinear travel of the structure responsive to lateral pressure thereon, detachably connected to said structure, body 60 supporting means detachably connected to said structure, and means on said structure whereby a hand-guided front rolling support may be substituted for the aforesaid front 65 supporting means.

3. In combination with a board formed as a saddle with a narrow forward portion to be straddled by the legs of the rider, rear wheels to support said board, and a caster mounting element secured to the board and 70 serving as a forward support, said element having casters located thereon at points spaced widely to give a wide wheel base for the board, said caster mounting element being removably mounted to the board, the 75 seat provided with a steering post hole for a single front steering wheel, said caster bar mounting element being independent of said single front steering wheel.

4. In combination with a board formed as 80 a saddle with a narrow forward portion to be straddled by the legs of the rider, rear wheels to support said board, and a forward 85 rolling support rigidly but removably secured to the board, said board having a hole near said forward support, in which the steering post of a steering wheel may be rotatably mounted after removal of said rigidly secured forward support.

POWEL CROSLEY, JR.
